DRY SHAVER

Maarten Willem van Lelyveld, Drachten, Netherlands, assignor to U.S. Philips Corporation, New York, N.Y.

Filed Aug. 14, 1972, Ser. No. 280,169

Claims priority, application Switzerland Feb. 14, 1972

Term of patent 14 years

Int. Cl. D28—03

U.S. Cl. D95—3 A

FIG. 1

FIG. 2

FIG. 3

FIG. 4

FIG. 5

FIG. 6

FIG. 7

FIG. 8

FIG. 1 is a perspective view of the dry shaver with the shaving head in line with the body, showing my new design;

FIG. 2 is a perspective view of the dry shaver of FIG. 1 with the shaving head thereof in an inclined position;

FIG. 3 is a right side elevational view of the shaver in FIG. 1;

FIG. 4 is a left side elevational view thereof;

FIG. 5 is a front elevational view thereof;

FIG. 6 is a rear elevational view thereof;

FIG. 7 is a top plan view thereof; and FIG. 8 is a bottom plan view thereof.

I claim:

The ornamental design for a dry shaver, as shown.
